US00D572614S

(12) **United States Design Patent**
McEwan et al.

(10) **Patent No.:** US D572,614 S
(45) **Date of Patent:** ** Jul. 8, 2008

(54) **PORTION OF A TAPE CASE**

(75) Inventors: **Sean Michael McEwan**, Raleigh, NC (US); **Brian D. Westbrook**, Raleigh, NC (US)

(73) Assignee: **Cooper Brands, Inc.**, Houston, TX (US)

(**) Term: **14 Years**

(21) Appl. No.: **29/285,272**

(22) Filed: **Mar. 26, 2007**

(51) LOC (8) Cl. **10-04**

(52) U.S. Cl. **D10/72**

(58) **Field of Classification Search** D10/72; 33/755-771; 242/292, 381.1-381.6

See application file for complete search history.

(57) **CLAIM**

The ornamental design for a portion of a tape case, as shown and described.

DESCRIPTION

This application is also related to co-pending application: Ser. No. 11/675,845, filed Feb. 16, 2007, and titled “Tape Measure with Interchangeable End Fittings” to Sean McEwan, Christopher T. Cluff, and Brian D. Westbrook, and co-pending application: Ser. No. 11/675,853, filed Feb. 16, 2007, and titled “Tape Measure with Moving Tape Exit Port” to Sean McEwan, Christopher T. Cluff, and Brian D. Westbrook.

FIG. 1 is a perspective view of a first embodiment of a portion of a tape case showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment thereof;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken line showing of structural features is included for the purpose of illustrating non-claimed subject matter and forms no part of the claimed design.
